UNITED STATES PATENT OFFICE.

CHARLES H. GOODYEAR, OF PORTLAND, OREGON.

FOLDABLE VENDING TRAY FOR ICE-CREAM CONES AND OTHER ARTICLES.

Application filed April 19, 1928. Serial No. 271,218.

My invention relates to foldable, portable stands or vending trays, especially adapted for use in handling articles such as ice cream cones, cups of soda waters, and like articles.

5 Stores selling refreshments along the highways, are frequently called upon to serve ice cream cones or beverages to a number of persons driving up in an automobile, who prefer to be served without getting out; 10 hence, if several trips between the store counter and the automobile are to be avoided, some tray must be used capable of carrying enough cones, or cups, for serving all of the party at one time.

15 The principal object of my invention is therefore to provide a simple, inexpensive foldable vending tray, made of cardboard or similar material, and adapted to be stored in quantities in a flat package, from which 20 units of these vending trays may be taken as required.

Further, to provide a tray of the character described which may be cut out of a single sheet of light cardboard, or similar material, by a single operation, without undue waste; and which may be readily set up for use.

25 A further object of my invention is to provide a vending tray of the character described which is so cheap to manufacture that it may be thrown away after having once been used, or given away, for advertising purposes, for future use.

30 A further object of my invention is to provide a vending tray of the character described adapted, when set up, to be used also as a display stand for the articles to be sold.

35 One convenient way in which my invention may be carried into practice consists in providing a vending tray comprising a body made of a sheet of material composed of two sides and a top, making a triangle in cross section, the sides provided with integral end portions adapted to be folded outward perpendicular with the planes of the sides and constituting the supporting element of the tray, the top provided with integral end extensions adapted to be folded down perpendicular with the plane of the top, and means for securing said end extensions of the top to said side extensions when the tray is set up; the parts being scored 40 to adapt the tray to be folded into a flat package; and preferably my foldable vending tray is made of a unitary blank com-

prising three parallel foldable sections separated by scores from each other.

Full details of the principle of construction embodied in my invention are herein- 60 after described with reference to the accompanying drawings; in which:

Fig. 1 shows my collapsible holder assembled, ready for use and illustrates a number of ice cream cones contained therein; 65

Fig. 2 shows my invention after it has been cut from a flat sheet of cardboard and scored;

Fig. 3 shows my invention assembled and folded flat ready to be packed in bundles 70 and shipped;

Fig. 4 shows a central transverse section of my vending tray when set up and illustrates the simple means provided for holding it in such position; and 75

Fig. 5 shows a section taken centrally through Fig. 3 and illustrates by broken lines the successive positions assumed by my tray while being set up.

A sheet of light cardboard or similar material is cut or punched to form a blank *a*, Fig. 2, in which circular article receiving holes *b* are provided, end portions *e* and end extensions *d*, also arcuate slits *p*. 80

The blank *a* is then scored transversely as at *j* and *j'* to make the end portions *e* and end extensions *d* conveniently foldable.

85 A longitudinal score *f* is provided along the outer side of the portion *c* in which the holes *b* have been cut, separating a marginal strip *g* to which adhesive may be applied. Another parallel score *h* is provided, which separates the portion *c* from the remainder of the sheet *a*.

90 A central parallel score *i* is provided in the portion *c* between the scores *f* and *h* and a score *k* is provided, parallel with the scores *f* and *h* and arranged centrally through the main portion of the sheet. A finger hole *l* is provided which is bisected 100 by the score *k*.

95 As the first step in assembling, the sheet *a* is folded on the scores *i* and *k* and the marginal strip *g* is fixed by adhesive or other suitable means, to the inside of the opposite margin *a'* of the sheet *a* as shown shown in Figs. 3 and 4. At the end of this 105 step my holder will be flat in the form as shown in Fig. 3, and may be conveniently packed in bundles for shipment.

110 For the last step, when my vending tray is to be used for distributing cones filled

with ice cream, Fig. 1, or other purposes, the two sides of the holder will be separated and folded along the scores *f* and *h*, the fold along the score *i* being flattened out, thus forming a vending tray triangular in cross section. The end portions *d* are then folded outwardly along the scores *j* and *j'* and the end extensions *e* are folded downwardly along the same scores and the corners inserted in the curved slits *p* in the end portions *d*.

By this construction, the end portions *d* form lateral supports for maintaining my vending tray in an upright position as when 15 arranged on a counter and the end extensions *e* being locked in the slits *p* form locking means for holding my tray in its assembled form either as a display stand or tray for distributing ice cream cones or 20 other salable articles through a crowd or the like.

I claim:

1. A foldable vending tray comprising a body made of a sheet of material and composed of two sides and a top making a triangle in cross section, the sides provided with integral end extensions adapted to be folded perpendicular with the planes of the sides and constituting the supporting element of the tray, the top provided with article receiving holes, the parts being scored to adapt the tray to be folded into a flat package as described and means for securing the tray in its set up state.

35 2. A foldable vending tray comprising a body made of a sheet of material and composed of two sides and a top making a triangle in cross section, the sides provided with integral end extensions adapted to be folded perpendicular with the planes of the sides and constituting the supporting element of the tray, the top provided with integral end extensions adapted to be folded perpendicular with the plane of the top, the 40 top provided with article receiving holes, means for securing said end extensions of the top to said end portions when the tray is set up and the parts being scored to adapt the tray to be folded into a flat package as described.

45 3. A foldable vending tray consisting of a unitary blank comprising three parallel foldable sections adapted to be arranged to form a triangle in cross section and constituting the sides and the top of the body of the tray, the side sections of the tray body provided with foldable end portions adapted to be arranged normal with the plane of the sides, and constituting the supporting element of the tray, the top body section provided with an article receiving hole or holes and means for securing the tray in its set up state.

60 4. A foldable vending tray consisting of a unitary blank comprising three parallel

foldable sections adapted to be arranged to form a triangle in cross section and constituting the sides and the top of the body of the tray, the side sections of the tray body provided with foldable end portions 70 adapted to be arranged normal with the plane of the sides, and constituting the supporting element of the tray, the top body section provided with an article receiving hole or holes, means for securing the tray 75 in its set up state and the top section provided with a score on its longitudinal central line permitting the folding of the tray into a flat package.

5. A foldable vending tray consisting of 80 a unitary blank having parallel scores made thereon dividing the blank into three foldable, parallel sections adapted to be arranged to form a triangle in cross section and constituting the sides and the top of 85 the body of the tray, the side sections of the tray body provided with foldable end portions adapted to be arranged normal with the plane of the sides, and constituting the supporting element of the tray, the top body section provided with an article receiving hole or holes and means for securing the tray in its set up state.

6. A foldable vending tray consisting of 95 a unitary blank having parallel scores made thereon dividing the blank into three foldable, parallel sections adapted to be arranged to form a triangle in cross section and constituting the sides and the top of 100 the body of the tray, the side sections of the tray body provided with foldable end portions adapted to be arranged normal with the plane of the sides, and constituting the supporting element of the tray, the top body section provided with an article receiving hole or holes, means for securing the tray in its set up state and the top section provided with a score on its longitudinal central line permitting the folding of the tray into a flat package.

7. A foldable vending tray consisting of 110 a unitary blank having parallel scores made thereon dividing the blank into three foldable, parallel sections adapted to be arranged to form a triangle in cross section and constituting the sides and the top of the body of the tray, the side sections of the tray body provided with foldable end portions 115 adapted to be arranged normal with the plane of the sides, and constituting the supporting element of the tray, the top section provided with foldable end extensions, the top body section provided with an article receiving hole or holes, means for fastening the free edges of the adjacent sections of the body together and means for securing the extensions of the top section of the tray body to the foldable extensions of its sides.

8. A foldable vending tray consisting of 120 a unitary blank having parallel scores made 125

- thereon dividing the blank into three foldable, parallel sections adapted to be arranged to form a triangle in cross section and constituting the sides and the top of the body of the tray, the side sections of the tray body provided with foldable end portions adapted to be arranged normal with the plane of the sides, and constituting the supporting element of the tray, the top section provided with foldable end extensions, 5 the body of the tray, the side sections of the tray body provided with foldable end portions adapted to be arranged normal with the plane of the sides, and constituting the supporting element of the tray, the top 10 section provided with foldable end extensions, the top body section provided with an article receiving hole or holes, one of the free longitudinal edges of the body sections being provided with a lip for fastening 15 to the free longitudinal edge of the adjacent body section and means for securing the extensions of the top section of the tray body to the foldable extensions of its sides.
9. A foldable vending tray consisting of 20 a unitary blank having parallel scores made thereon dividing the blank into three foldable, parallel sections adapted to be arranged to form a triangle in cross section and constituting the sides and the top of the body 25 of the tray, the side sections of the tray body provided with foldable end portions adapted to be arranged normal with the plane of the sides, and constituting the supporting element of the tray, the top section 30 provided with foldable end extensions, the top body section provided with an article receiving hole or holes, means for fastening the free edges of the adjacent sections of the body together and the said end extensions 35 of the tray body provided with slits for receiving the corners of the end extensions of the said top section.
10. A foldable vending tray consisting of a unitary blank having parallel scores made 40 thereon dividing the blank into three foldable, parallel sections adapted to be arranged to form a triangle in cross section and constituting the sides and the top of the body of the tray, the side sections of the 45 tray body provided with foldable end por-
- tions adapted to be arranged normal with the plane of the sides, and constituting the supporting element of the tray, the top section provided with foldable end extensions, said end portions of the body sides having 50 portions cut away in alinement with the fold connecting the tray body sides whereby the bases of these extensions will be normal with the perpendicular of the said triangle formed by the tray body when set up, the 55 top body section provided with an article receiving hole or holes, means for fastening the free edges of the adjacent sections of the body together and means for securing the extensions of the top section of the tray 60 body to the foldable extensions of its sides.
11. A foldable vending tray consisting of a unitary blank having parallel scores made thereon dividing the blank into three foldable, parallel sections adapted to be arranged to form a triangle in cross section and constituting the sides and the top of the body of the tray, the side sections of the tray body provided with foldable end 65 portions adapted to be arranged normal with the plane of the sides, and constituting the supporting element of the tray, the top section provided with foldable end extensions, said end portions of the body sides having 70 portions cut away in alinement with the fold connecting the tray body sides whereby the bases of these extensions will be normal with the perpendicular of the said triangle formed by the tray body when set up, the 75 top body section provided with an article receiving hole or holes, means for fastening the free edges of the adjacent sections of the body together, means for securing the 80 extensions of the top section of the tray body to the foldable extensions of its sides and the top section provided with a score on its longitudinal central line permitting the folding of the tray into a flat package.

CHARLES H. GOODYEAR.
